(57) **CLAIM**

The ornamental design for a housing for a location tracker, as shown and described.

DESCRIPTION

FIG. 1 is a perspective view of a housing for a location tracker, showing our new design;

FIG. 2 is a front view of the housing for a location tracker;
FIG. 3 is a right side view of the housing for a location tracker;

FIG. 4 is a top view of the housing for a location tracker;
FIG. 5 is an exploded perspective side view of the housing for a location tracker;

FIG. 6 is an exploded right side view of the housing for a location tracker;

FIG. 7 is a bottom perspective view of a top component of the housing for a location tracker;

FIG. 8 is a top perspective view of a bottom component of the housing for a location tracker;

FIG. 9 is a top perspective view of the top component of the housing for a location tracker;

FIG. 10 is a bottom perspective view of the bottom component of the housing for a location tracker;

FIG. 11 is a bottom view of the top component of the housing for a location tracker;

FIG. 12 is a top view of the top component of the housing for a location tracker;

FIG. 13 is a right side view of the top component of the housing for a location tracker;

FIG. 14 is a right side view of the bottom component of the housing for a location tracker;

FIG. 15 is an exploded perspective view of the housing for a location tracker, illustrating an exemplary location tracker in broken lines; and,

FIG. 16 is a perspective view of the housing for a location tracker, illustrating the housing for a location tracker mounted on an exemplary bicycle shown in broken lines.

(Continued)

The broken lines depict portions of the housing for a location tracker that form no part of the claimed design, and environment that forms no part of the claimed design.

1 Claim, 8 Drawing Sheets
